UNITED STATES PATENT OFFICE.

HARRY H. SCHROYER, OF CHICAGO, ILLINOIS, ASSIGNOR TO THE ACME SUPPLY COMPANY, A CORPORATION OF ILLINOIS.

CAR-VESTIBULE DIAPHRAGM.

1,082,241.

Specification of Letters Patent. Patented Dec. 23, 1913.

Application filed May 10, 1913.. Serial No. 766,713.

To all whom it may concern:

Be it known that I, HARRY H. SCHROYER, a citizen of the United States, and a resident of the city of Chicago, in the county of

5 Cook and State of Illinois, have invented a new and useful Improvement in Car-Vestibule Diaphragms, of which the following is a specification.

As heretofore constructed V-shaped or 10 angled vestibule diaphragms have afforded lodgment for sparks and cinders, thereby causing great wear and damage to the diaphragm and decreasing the life thereof. Other diaphragms have been constructed entirely of U-form, but the U-form has been found to afford insufficient support in the legs of the diaphragm for the arched top, thereby allowing sagging of the same, and eventually serious damage thereto.

20 This invention relates to that class of diaphragms adapted for engagement between the diaphragm face plate and the vestibule face plate of a railway car to afford a flexible connection therebetween. The legs 25 are constructed of accordion folds of angled or V-shaped section, and the top is of U-form section.

It is an object of this invention to afford a 30 diaphragm so constructed as to be entirely self-cleaning from dirt and sparks, and to afford a top section into which water or moisture cannot find access, thereby preventing rotting of the fabric.

It is also an object of this invention to 35 afford a construction wherein any desired number of strips of fabric are clenched together to afford the angled legs of a vestibule diaphragm, and one wherein the top sections are clenched only at their outer 40 edges, thereby affording a combined U-form and angled vestibule diaphragm.

It is also an object of this invention to 45 provide suitable reinforcing means for the top sections adapted to extend down into the legs of the diaphragm.

It is furthermore an object of this invention to construct angled vestibule diaphragm legs which merge into a diaphragm top of U-form.

50 It is finally an object of this invention to provide a combined U-form and V-shaped or other angled vestibule diaphragm with an integral reinforcing element extending into each of said portions.

The invention embraces many novel features and in a preferred form is illustrated in the drawings and hereinafter more fully described.

In the drawings: Figure 1 is a front view of a vestibule diaphragm with one section removed and the binding elements shown in section. Fig. 2 is a side elevation thereof. Fig. 3 is an enlarged fragmentary detail illustrating the connection between the top and leg sections of the diaphragm. Fig. 4 is a section taken on line 4—4 of Fig. 1. Fig. 5 is a section taken on line 5—5 of Fig. 1. Fig. 6 is an enlarged detail section taken on line 6—6 of Fig. 4, to illustrate the staple clenching means. Fig. 7 is a fragmentary side elevation thereof.

As shown in the drawings: The reference numeral 1, designates the leg sections of the diaphragm, which are shown as a single continuous strip of fabric with stitching 2, extending for almost the entire length thereof and serving to clench the walls together into angled relation. However, it is not essential that the legs be constructed of a single continuous strip of fabric, as obviously a plurality of such strips may be used and connected together to effect the same purpose.

The top portion of the diaphragm is composed of a plurality of short sector shaped sections numbered 3, 4, and 5, respectively, and the relative long sections 6, said sections stitched together and arranged in overlapping relation to readily shed water, dirt, or other particles falling thereupon. The outer edges of said top and leg sections are secured together by means of the channel shaped elements 7, which engage therearound, and may be either constructed of metal or may comprise a strip of fabric, as desired.

Inclosed thereby, and within the inner surfaces of the margins of the diaphragm fabric sections, are the continuous integral reinforcing elements 8, which extend entirely across the top portion of the diaphragm sections and down into legs thereof, and are suitably apertured to receive the staples 9, therethrough, which are clenched on the outer surface of said elements 6, to bind the whole securely together.

As illustrated in the drawings I have shown the reinforcing element 8, as extending entirely for the whole length of the leg sections of the diaphragm, but this is not

essential, and may be influenced to a great extent by the number of folds used in the diaphragm.

Referring to Figs. 1, 3, and 4, it will be noted that the reinforcing elements 8, is of greater depth at the top of the diaphragm, especially at the sharper curves, while the portions extending into the leg taper toward their ends. I have shown and described this reinforcing element as an integral piece of metal, although it is obvious that this is not necessarily so, but it simplifies the construction. The purpose of constructing the upper section of the vestibule diaphragm 15 of U-form is to insure the shedding of sparks, water or other such matter therefrom, while on the other hand the leg portions of said sections are clenched at the inner sides thereof to reinforce and stiffen 20 the same. This is feasible in the leg portions of the diaphragm for the reason that foreign particles have no tendency to adhere or be retained in the angle thus formed, owing to the vertical position of such portions. 25

In Figs. 4, and 5, I have illustrated one end of the vestibule diaphragm as attached to a car end 10, and with the other end of said diaphragm secured to a face plate 11, 30 adapted for attachment to another car end or a similarly disposed vestibule diaphragm. However, this latter construction forms no part of my present invention and I have merely shown the same as such for convenience of illustration. 35

I am aware that details of construction may be varied through a wide range without departing from the principles of this invention. I therefore do not purpose limiting the patent granted otherwise than necessitated by the prior art. 40

I claim as my invention.

1. A vestibule car diaphragm comprising leg sections and top sections in register with 45 one another, said top sections of U-form, and said leg sections of angled form.

2. In a device of the class described a unitary reinforcing element for the top sec- 50

tions of an arched vestibule diaphragm extending downwardly into the legs thereof on each side, said elements enlarged at the arched portion. 55

3. In a device of the class described a vestibule diaphragm comprising top and leg sections secured together, said top sections of U-form, and said leg sections of angled form, and reinforcing elements inserted between and extending around adjacent dia- 60 phragm sections. 65

4. In a device of the class described a plurality of diaphragm sections, a reinforcing element inserted therebetween of varying width, and means secured on the outer edges of said adjacent sections to bind the same together and to said reinforcing element 65 within the same. 60

5. In a device of the class described a dia- 70 phragm leg section stitching centrally there- of for a portion of the length, said arrange- ment affording a continuous trough of both U-form and angled sections. 70

6. In a device of the class described a vestibule diaphragm top section composed of a plurality of sector shaped elements, leg sections secured thereto and conforming to 75 the shape thereof, and means extending for a portion of the length of said leg sections to reinforce and change the shape thereof. 75

7. In a car vestibule diaphragm top sec- 80 tions of U-form and leg sections connected thereto and stitched so as to be both of a U-form and an angled section. 80

8. In a device of the class described the combination with the reinforcing element of top sections of U-form, and leg sections con- 85 nected thereto, said leg sections stitched for a portion of their length affording sections of U-form and angled or V-shaped. 85

In testimony whereof I have hereunto subscribed my name in the presence of two 90 subscribing witnesses.

HARRY H. SCHROYER.
